UNITED STATES PATENT OFFICE.

CHARLES TURNER, OF CHICAGO, ILLINOIS.

ATTACHMENT FOR LOCOMOTIVE SMOKE-STACKS.

SPECIFICATION forming part of Letters Patent No. 340,259, dated April 20, 1886.

Application filed October 15, 1884. Serial No. 145,614. (No model.)

To all whom it may concern:

Be it known that I, CHARLES TURNER, a citizen of the United States, and residing at Chicago, in the county of Cook and State of Illinois, have invented certain new and useful Improvements in Attachments for Locomotive Smoke-Stacks, which are fully set forth in the following specification, reference being had to the accompanying drawings, in which—
10 Figure 1 is a side elevation of a locomotive having my device attached to its smoke stack; Fig. 2, a front elevation of my device attached to a smoke-stack; Fig. 3, a plan view of the same; and Fig. 4, a sectional view on the line xx of Fig. 3, a portion being also shown on an enlarged scale.

Like letters refer to like parts in all the figures.

My invention relates to devices to be attached to locomotive smoke-stacks in order to prevent the smoke and cinders issuing therefrom from descending upon the train; and to that end it consists in certain novel features, which I will now proceed to describe, and 25 then specifically point out in the claims.

In the drawings, A indicates a locomotive of the usual construction, and B the smoke stack thereof. At the front of the locomotive I attach a large funnel, C, from the rear end of 30 which a large pipe, c, extends upward in front and nearly to the top of the smoke-stack B. From the upper end of pipe c a smaller pipe, D, surrounding the smoke-stack, branches out, as shown, the two divergent portions extending upward and rearward, as shown, and the upper portion, D', being located back of and somewhat below the opening b of the smoke-stack at its broadest point. This upper horizontal portion, D', of pipe D has a 35 slot, d, as shown, extending the entire length of its upper side. To the front side of the part D', I attach a guard, E, consisting of a plate extending upward as high as the extreme upper edge of the smoke-stack. This 40 guard-plate also serves to secure the pipe to the stack.

The operation of my device is as follows: When the locomotive is in motion, the air enters the funnel C and passes up through pipe c into pipe D, finally issuing from slot d in a sheet with great force. This sheet of air forms a shield or barrier immediately behind the orifice b, from which the smoke issues, preventing it from passing immediately backward and downward upon the train. The air-shield causes the body of smoke and cinders to rise to a height sufficient to carry it clear of the train. By this means one of the most objectionable features of traveling is avoided.

The guard E prevents any breaking of the air-current before it has reached a position in which it will be operative. This shield may, however, be dispensed with, although I deem its use preferable.

It is obvious that many mechanical modifications may be made in the construction without departing from the principle of my invention, and I therefore do not wish to be understood as limiting myself to the precise details of construction shown and described.

Having thus described my invention, what I claim as new, and desire to secure by Letters Patent, is—

1. The combination, with a locomotive smoke-stack, of pipe D, encircling the same, and having the slotted portion D' around the rear upper edge of the stack, and a pipe, c, connecting pipe D with a funnel, C, arranged as described, substantially as and for the purposes specified.

2. The combination, with the smoke-stack B, of pipe D, having slotted portion D', arranged as described, guard E, attached thereto, pipe c, and funnel C, substantially as and for the purposes specified.

CHARLES TURNER.
